UNITED STATES PATENT OFFICE.

GERHARD P. HELMERS, OF BALTIMORE, MARYLAND.

CUFF.

1,105,779.

Specification of Letters Patent.

Patented Aug. 4, 1914.

Application filed October 31, 1913. Serial No. 798,429.

To all whom it may concern:

Be it known that I, GERHARD P. HELMERS, a citizen of the United States, residing at Baltimore city, State of Maryland, have invented certain new and useful Improvements in Cuffs, of which the following is a specification.

My invention relates to cuffs, and has reference more particularly to what are known as soft cuffs, that is, a cuff in which starch or its equivalent has been omitted in the laundering thereof, it being understood however that my invention is not limited to this particular class of cuffs, and that it is equally applicable to what are known as stiff or starched cuffs, and is not confined to any particular style or shape cuff.

The object of the invention is to provide a cuff which can be fashioned from linen or any suitable material in which the button shank receiving holes are so arranged and constructed that the cuff buttons can be inserted therein with great ease, and can be easily removed, which obviates the usual difficulty and annoyance occasioned by the operation of securing cuff buttons through the holes against disengagement, and which minimizes the wear upon the button holes, incident to the insertion and removal of the buttons, the button holes being so arranged with relation to the body part of the cuff that when the buttons are inserted through the button holes, the possibility of the buttons becoming disengaged from the button holes and probably lost is reduced practically to a minimum.

The tendency of a cuff button to become disengaged from the button hole of a cuff constructed in accordance with this invention is to a degree practically obviated, and for this reason the invention is particularly applicable to soft or unstarched cuffs which by reason of their flimsiness the tendency of the buttons to become disengaged from the button holes is more or less apparent.

The invention further consists in certain novel features of construction, combinations and arrangement of parts, which will be more fully described and particularly set forth in the claim, reference being had to the accompanying drawings forming a part of this specification, in which a preferred embodiment of my invention is illustrated,

and in which similar characters of reference indicate corresponding parts in all the several views, and in which,—

Figure 1 is a perspective view of my improved cuff when made for use with a link cuff button; Fig. 2 is an enlarged fragmentary detail view of the same; Fig. 3 is a plan view of the cuff shown in Fig. 1.

Referring to the drawings, A indicates the body part of the cuff, having the usual corners 1 and 2, it being understood that the corners of the cuff, the general shape or style, may be other than shown, these features forming no part of my invention; 3 indicates the front edge and 4 the rear edge of the cuff.

In the body part A of the cuff, located a predetermined distance from the corners 1 and 2, are provided button holes 5 and 6 respectively. These button holes are arranged in angular relation to the body part A of the cuff and in parallel relation to each other, the angular relation being such that when the cuff is folded and secured in folded position by means of the ordinary link button indicated at 7 in Fig. 1, the button holes 5 and 6 will lie crosswise, that is they will cross each other as shown in Fig. 2, and by reason of such the possibility of disengagement and loss of the button is to a more or less degree obviated as compared with a cuff in which the button holes are constructed so that when the cuff is folded the button holes lie in the same plane.

Having fully described my invention, what I claim, and desire to secure by Letters Patent, is;—

A cuff for link buttons, comprising a body-part having button-holes provided therein, said button-holes being formed in the corners of the cuff adjacent to the outer edge thereof and inclined relative to said edge and parallel with each other, whereby they will cross each other when the cuff is folded with the meeting edges together and the inner surface of the cuff adjacent said meeting edges in contact.

In testimony whereof I affix my signature in presence of two witnesses.

GERHARD P. HELMERS.
